UNITED STATES PATENT OFFICE

1,982,703

FORMER FOR PRINTING MACHINES

William J. Strain, Upper Montclair, N. J., assignor to R. Hoe & Co., Inc., New York, N. Y., a corporation of New York; Irving Trust Company, temporary trustee

Application April 20, 1932, Serial No. 606,383

14 Claims. (Cl. 270—86)

This invention relates to improvements in formers for printing machines, with particular reference to those used in connection with machines of the high speed rotary type. The former referred to, is one which doubles or makes the preliminary fold, longitudinally and centrally of a multiple running web, and it has been found that those of fixed conformation, as heretofore used, occasion various difficulties.

10 Present practice now requires speeds of translation of the webs more than twice as great as those of a comparatively few years ago, and, in addition to this, newspapers now have, at times, a much greater number of pages than those formerly produced.

In running a plurality of associated webs over the prior type of former, of fixed conformation, it has been found that an increased advance to suit present high speed practice causes frequent buckling of some of the webs as the time element must be considered and provided for in order to produce the best results.

It has also been found that with an increase in the number of sheets and the consequent greater thickness of a multiple web, the tension of the outer sheets, due to the necessarily curved delivery, is so great that the prior types of formers break or tear some of them, besides crumpling the inner sheets of the group.

30 It is one of the objects of this invention to provide a former with a flexible and adjustable nose portion which will be conformed to operate successfully upon multiple webs at various and, at high speeds and also to operate favorably upon a thin running web composed of a few sheets as well as on a thicker one comprising a large number of sheets, and by reason of its construction and mode of action the difficulties hereinbefore recited are overcome.

40 In order to attain the improved results by means of this invention the former is constructed with an end or nose portion which is mechanically adjustable, and it is also inherently elastic, flexible and yielding so that its end portion, 45 which projects in the fashion of a cantilever, is further self-adjustable automatically.

By means of this construction the improved former nose can be shaped and positioned and it also further automatically conforms itself to make the preliminary longitudinal fold in a running web composed of any number of superimposed sheets and at various working speeds, and this dual adjustability obviates the difficulties hereinbefore mentioned.

55 It is also an object of the invention to provide

a former for a running web of generally improved construction which is simple, durable and inexpensive in construction as well as convenient, practical, serviceable and efficient in use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawing wherein:

Figure 1 is a side elevation of the improved former;

Figure 2 is a front elevation thereof looking in the direction of the arrow 2 of Figure 1;

Figure 3 is a side elevation of the improved flexible and adjustable nose portion of the former; and

Figure 4 is a rear elevation thereof viewed in the direction of the arrow 4 of Figure 3.

Referring now to the characters of reference on the drawing:

A portion of a cross frame for the machine and which supports the former is indicated as 11 85 while 12 is a portion of a rear side frame of the apparatus. A portion of the top frame is indicated as 13 and a part of a front side frame is indicated as 14.

The former generally is indicated as 15 and its body is preferably composed of a thin plate of steel which is supported and reinforced at its edges by round bars or shafts 16 forming the curved edged portions of the former in order to smoothly guide the web as it is flexed thereover.

90 The former is mounted upon the carriage 17, which is adapted to support it, and by the operation of the hand-wheel 20 and its connections is capable of movement laterally in the directions indicated by the arrows on Figure 2, in order to 100 accommodate webs of different widths and to position them relatively thereto so as to insure a central longitudinal fold therein.

In order to vary the inclination of the former 15 a rod 18 is pivoted thereto as indicated and capable of being moved longitudinally and positioned by means of the adjusting nut 19 and its companion jam nut 21. The former 15 is further supported by the bracket or rocker arm 22 which is capable of a swinging movement about the rock. 110

shaft 23 whereby it may be slightly adjusted in inclination by the nuts 19 and 21 in order to insure the accurate tracking of the running web W, and to fix the position of its upper end adjustment to but not tracking the roller 24.

The web W is delivered to the drag roller 24 which is mounted on the driven shaft 25 and thence passes downwardly in an inclined direction over the generally triangular former 15 and is given an initial fold thereby. The shaft 25 is rotatably supported in end bearings carried by the frame and is also centrally supported by a bearing at the upper end of the post 26.

The flexible nose portion of the former, which is preferably composed of a thin elastic steel plate, is indicated as 27 and this is secured to the more rigid body portion of the former 15 by the tap screws 28. On the inner side of the flexible nose portion 27 a bracket 29 is secured, which is provided with the pivot pin 31 as shown, and near the lower end of the rigid upper portion of the former 15, a fulcrum bracket 32 is secured thereto and this is provided with a fulcrum pin 33. Another pivot pin 34 is provided to pivotally connect the upper end of the lever 35, to the inner end of the adjusting rod 36 the rear end of which is screw-threaded and provided with an adjusting nut 37 and a jam nut 38 in order to move and position it with respect to the carriage 17. Bearing blocks 39 and 41 are mounted on the base frame 11 and carry the rotatable shafts 42 and 44 on which are respectively mounted the un-driven bending rollers 43 and 45.

Having thus given a description of the mechanism, a résumé of its mode of operation will be of interest.

The drag roller 24 is driven by any suitable source of power and the web W is advanced by it, whereupon it passes over the former 15 which forms the initial fold. This running web W may be composed of any number of plies or thicknesses and, as it passes over the flexible nose 27, this nose, by reason of its thinness and manner of support is adapted to flex and accommodate itself to the movement of the web and to the forces thereby applied to it. The nose portion 27 is preferably formed from an integral steel plate which is inherently and elastically flexible.

In order to arrange the adjustable nose to the best advantage, it may be less curved when a web composed of a large number of plies is being initially folded and may have a greater curvature when a thinner multiple web is being folded. This adjustment is made mechanically by moving the adjusting rod 36 longitudinally either backward or forward and securing it in the position desired by means of the adjusting nut 37 and the jam nut 38 and this may be done either before the operation begins or if found necessary the conformation of the nose can be adjusted while the web is running in order to produce the best results.

It has been found that a thin multiple web will run without difficulty over a nose of greater curvature, while a thicker web or one of more plies requires less curvature in order to be smoothly delivered without crumpling, tearing or breaking some of the plies.

In addition to this mechanical means of producing the desired curvature in the nose, it should be noted that its outer end portion overhangs the bracket 29 to a certain extent in the form of a projection or cantilever, and as this is elastically flexible it will yield to any irregularities of and to any excess or deficiency of pressure applied to it

by the running web, so that its end portion automatically adjusts itself in accordance with the work to be performed.

It will be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

What I claim is:

1. A former for a running web, said former being equipped with a flexible nose portion, and means for adjusting the curvature of said nose portion.

2. In a former for a running web, an elastically flexible nose portion therefor, and means for flexing said nose portion to adjust the curvature thereof.

3. In a former for a running web, a flexible nose secured thereto, and means for adjusting the curvature of that portion of the nose adjacent to the former.

4. In a former for a running web, an inherently flexible nose secured thereto, and means for flexing said nose relatively to said former.

5. In a former for a running web, an inherently flexible nose secured thereto, and means acting upon the intermediate portion of said nose adapted to bend it relatively to said former.

6. In a former for a running web, an inherently flexible nose portion secured thereto, means acting upon the intermediate portion of said nose adapted to flex it relatively to said former, the outer end of said nose projecting beyond said means and adapted to bend in proportion to the forces applied thereto by said web.

7. The combination with a running web, of a former adapted to initially fold it, an inherently flexible nose secured to the delivery end of said former, means for positioning the portion of said nose adjacent the former, said nose having an integral end portion extending from its fixed portion and thereby adapted to automatically flex due to the forces applied thereto by the running web.

8. In a former for a running web, an inherently elastically flexible nose portion extending therefrom and adapted to automatically conform its curvature to the forces applied thereto by the running web.

9. In a former for a running web, an integral inherently elastic tapering nose the wider portion of which is secured to said former, with its narrower portion extending unsupportedly therefrom and adapted to flex in proportion to the pressures applied to it by the running web.

10. In a mechanism of the character described, a former, an inherently flexible nose portion secured thereto, a lever secured to said nose, and means for rocking and securing said lever, whereby said nose is flexed as desired.

11. In a mechanism of the character described, a former, an inherently flexible nose the inner end of which is secured to said former, a lever, one end of which is pivoted to said nose with its central portion fulcrumed on the former, and means for rocking and securing said lever, whereby the nose is flexed as desired.

12. In a mechanism of the character described, a former, an inherently flexible nose secured thereto and projecting therefrom, a lever fulcrumed on said former with one end pivoted to

- the intermediate portion of said nose, the other end of said lever being connected to an adjusting rod, and means for adjusting and securing said rod, whereby the nose is flexed as desired.
- 5 13. A former of the character described comprising in combination, a body portion, elastic means detachably secured to said body portion, and manually operable means for varying the shape of said elastic means.
- 10
14. A former of the character described comprising in combination, a body portion, elastic means attached to said body portion, means for moving said body portion and elastic means in unison, and means for adjusting the elastic means independently of said body portion.
